(57) **CLAIM**

The ornamental design for a surgical stapler handle, as shown.

DESCRIPTION

FIG. 1 is a Perspective View of the surgical stapler handle.

FIG. 2 is a Top View thereof.

FIG. 3 is a Left Side View thereof.

FIG. 4 is a Right Side View thereof.

FIG. 5 is a Bottom View thereof.

FIG. 6 is a Front View thereof; and,

FIG. 7 is a Rear View thereof.

1 Claim, 4 Drawing Sheets

FIG. 1

FIG. 2

FIG. 3

FIG. 4

FIG. 5

FIG. 6

FIG. 7
